UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

TWIN-GOVERNOR MECHANISM FOR MIXED-PRESSURE TURBINES.

1,089,709.

Specification of Letters Patent. Patented Mar. 10, 1914.

Continuation of application Serial No. 641,015, filed July 28, 1911. This application filed November 10, 1911. Serial No. 659,474.

To all whom it may concern:

Be it known that I, OSCAR JUNGGREN, a citizen of the United States, residing at Schenectady, county of Schenectady, State 5 of New York, have invented certain new and useful Improvements in Twin-Governor Mechanism for Mixed-Pressure Turbines, of which the following is a specification.

The present application is a continuation 10 of my application, Serial No. 641,015, filed July 28th, 1911.

This invention relates to what are known as mixed pressure turbines, or in other words, elastic fluid turbines driven normally 15 by steam or other elastic fluid at a low pressure, but provided with means for admitting steam or other elastic fluid at high pressure whenever it becomes necessary to supplement the supply of low pressure fluid 20 in order to carry an increased load, or to compensate for a drop in the supply of low pressure fluid. The high pressure is thus held in reserve, as it were, to be used in case of necessity, and the customary arrangement 25 is to govern such a machine by means of one speed governor, in which half of its stroke is assigned to the low pressure valve mechanism of the machine and the other half to the high pressure valves. The same result 30 can be accomplished by using two speed governors, both geared to the turbine shaft, one governor controlling the low pressure admission and the other the high pressure admission. The governors are so constructed 35 that they operate in succession, the one controlling the low pressure steam and turning the admission valve almost wide open before the other governor begins to open the high pressure admission valves. 40 The closing of the valves takes place in the reverse order. This arrangement is practically the same as when one governor alone is utilized to control both steam pressures, but it has a distinct advantage in that by 45 means of a compensating device the high pressure valves can be brought into operation out of their usual time, if necessary, and independently of their own governor. This can be done either without interfering 50 with the operation of the low pressure governor, or on the other hand the compensating device can be caused to close the low pressure valve simultaneously with the opening of the high pressure valves. The

object of this arrangement is to compensate 55 for a drop or interruption of the supply of low pressure steam in the case of a mixed pressure turbine driving an alternating current generator coupled in parallel with other alternators driven by other prime 60 movers and independently governed and which are not subject to variations in steam pressure. Under such conditions, the mixed pressure unit will run at the same speed 65 as the others even when there is a deficiency of low pressure steam. Governors responsive to speed variations only will therefore be inadequate to effect the valve changes required to supplement this deficiency by a supply of high pressure steam. I therefore 70 provide the compensating device above referred to, comprising a movable abutment, such as a flexible diaphragm, exposed on one side to the fluid pressure in the low pressure conduit, and on the other side to atmospheric pressure, and biased against the atmospheric pressure by a spring or its 75 equivalent. The diaphragm is connected, through a lost motion device, with the high pressure governor, so that when the pressure 80 in the low pressure conduit becomes reduced below the value necessary for carrying the load, the diaphragm will be flexed by the air pressure against the spring and that of the pressure of the low pressure 85 source and will cause the governor to open its valves and admit high pressure steam, independent of the speed of the machine. By this device, the mixed pressure unit will carry approximately the same load, whether 90 it has the full amount of low pressure steam supplied to it, or only a reduced quantity supplemented by high pressure steam, and in either case at normal speed.

In many installations it is desirable never 95 to permit the pressure in the low pressure conduit to fall below that of the atmosphere, because in that case air will be sucked into the system and break down the vacuum in the condenser. This can be prevented by 100 connecting the diaphragm of my compensating device not only with the high pressure governor but also with the low pressure governor, so that as soon as the high pressure valve or valves is or are opened the low 105 pressure valve will be closed and will remain so until the pressure in the low pressure conduit is restored to atmospheric or above.

- The accompanying drawings are end elevations, partly in section, of a mixed pressure turbine equipped with twin speed governors and my compensating device, Figure 5 1 showing it applied to the high pressure governor only, and Fig. 2 showing the arrangement for closing the low pressure valve when the high pressure valve is opened by said compensating device.
- 10 The turbine has a casing 1 supported on a base 2. It is supplied with low pressure steam through a conduit 3 and with high pressure steam through a main 4, controlled respectively by the butterfly valves 5, 6.
- 15 The spindles of these valves are respectively connected to the operating motors, and as these motors are identical in construction, a description of one will suffice for both.
- The valve spindle is connected with a rod 20 7 attached to a movable abutment, preferably a piston 8 working in a cylinder 9. A pilot valve 10 in a valve chest 11 controls ports leading to the ends of said cylinder. Fluid under pressure is conveyed to the 25 valve chest by a pipe 12, the exhaust being led off by the pipe 13. The stem 14 of the pilot valve is pivoted to a floating lever 15, one end of which is pivotally connected to a follow-up lever 16, fulcrumed on the valve 30 chest and pivoted to the rod 7. The other end of the floating lever is connected by a link 17 with the transmission lever 18 of the governor. Upon a decrease of speed, the 35 governor weights fall and the transmission lever is moved upward, raising the pilot valve and admitting fluid pressure above the piston to open the butterfly valve more or less and decrease the supply of steam to the turbine. If the speed runs up above normal, the butterfly valve is correspondingly closed to reduce the flow of steam.
- I provide two speed governors, one of them 19 controlling the motor which operates the low pressure butterfly valve 5, and 40 the other one 20 controlling the high pressure valve 6. Both governors are geared to the turbine shaft 21, but their weights and spring tension are so adjusted that they operate in succession, as explained above.
- 45 My compensating device consists of a flexible metallic diaphragm 22 inclosed in a casing 23 which is connected by a pipe 24 with the low pressure conduit 3 in advance of the valve 5. A stop valve 25 controls the pipe 24. Acting in conjunction with the pressure of the steam against the diaphragm is a spring 26, whose tension can be adjusted by a screw 27 tapped through the top of the casing. This spring is so adjusted that the 50 diaphragm will not move upwardly until the steam pressure in the conduit 3 drops to atmospheric or thereabout. A rod 28 is attached to the diaphragm and passes through a bearing 29 in a bridge piece below the casing. It will thus be seen that the under side of the diaphragm is exposed to atmospheric pressure. A lever 30 is fulcrumed to a stud 31 on said bridge piece, and is pivoted to said rod. A link 32 connects said lever with the transmission or governor actuated lever of the high pressure governor by a lost motion device, such as a pin and slot, as shown, so that the governor is free to act under normal conditions, that is, so long as the supply of low pressure steam is maintained. But in case the pressure in the conduit 3 drops to that of the atmosphere, the 55 pressure on the diaphragm 22 is lessened sufficiently to permit the air pressure acting on its under side to force up the rod 28 and raise the levers 30 and 18 and operate the pilot valve of the high pressure valve motor to admit fluid pressure above the piston of said motor and cause the opening of the valve 6 to a greater or less extent, so as to admit sufficient high pressure steam to compensate for the drop in the low pressure conduit. This action of the compensating device is of course supplemental to that of the high pressure governor, and is effective 60 only when the speed of the machine persists in spite of the drop in low pressure steam, owing to the effect of the electrical connection between the alternator driven by this turbine and those driven by other engines. 65
- From the foregoing it will be seen that the turbine under heavy load conditions will use all the steam from the low pressure source and also a greater or less amount of steam from the high pressure source. So long as the low pressure source does not decrease in pressure below a certain predetermined amount the diaphragm mechanism will remain inactive but it is always on guard to modify the action of the high pressure speed governor whenever the steam supply conditions become abnormal. 70
- Fig. 2 shows the arrangement for closing the low pressure conduit when the pressure falls to atmospheric, in order to prevent air 75 from being sucked into the system. The lever 30 is replaced by a double-armed lever 33, one end of which is connected with the high pressure governor, as before. The other end of said lever is connected by a link 34 and a lost motion device with the transmission lever of the low pressure governor. When the air pressure forces the diaphragm upward against the spring 26 it raises the rod 28 and actuates the lever 33 to 80 open the valve 6, the downward movement of the link 34 occurring at the same time causes the low pressure valve-motor to close the valve 5 and thus prevent air from leaking into the turbine. 85
- If the failure of the low pressure source is only partial, the valve 5 will partially close thereby maintaining a pressure in the conduit 3 that is sufficiently high to prevent air leaks. 90

In accordance with the provisions of the patent statutes, I have described the principle of my invention, together with the apparatus which I now consider to represent 5 the best embodiment thereof; but I desire to have it understood that the apparatus shown is only illustrative and that the invention can be carried out by other means.

What I claim as new and desire to secure 10 by Letters Patent of the United States is:

1. The combination with a mixed pressure turbine, of twin speed governors, controlling respectively the low pressure conduit 15 and the high pressure main, and a compensating device responsive to a drop in pressure in the low pressure conduit and operating to open the high pressure main independently of its governor.
2. The combination with a mixed pressure turbine, of twin speed governors, controlling respectively the low pressure conduit and the high pressure main, a diaphragm exposed to the pressure in the low pressure 25 conduit, and operative connections between said diaphragm and the high pressure governor.
3. The combination with a mixed pressure turbine, of twin speed governors controlling 30 respectively the low pressure conduit and the high pressure main, a diaphragm exposed to the pressure in the low pressure conduit, and connections between said diaphragm and the transmission lever of the 35 high pressure governor, said connections including a lost motion device.
4. The combination with a mixed pressure turbine, of twin speed governors controlling respectively the low pressure conduit and 40 the high pressure main, means responsive to a drop in the low pressure fluid, and operative connections whereby said means can close the low pressure conduit and admit high pressure steam independently of said 45 governors.
5. The combination with a mixed pressure turbine, of twin speed governors controlling respectively the low pressure conduit and the high pressure main, a diaphragm exposed 50 to the low pressure fluid, a spring acting on said diaphragm, a lever connected with the diaphragm, and lost motion connections between said lever and the transmission lever of the high pressure governor.
6. The combination with a mixed pressure turbine, of twin speed governors controlling respectively the low pressure conduit and the high pressure main, a diaphragm exposed 55 to the low pressure fluid, a spring acting on said diaphragm, a lever connected with said diaphragm, and lost motion connections between said lever and the transmission levers of both of said governors.
7. The combination with a mixed pressure 60 turbine, of a low pressure supply conduit

and a high pressure supply main therefor, a butterfly valve in each of said supply pipes, a fluid-pressure operating-motor for each of said valves, twin speed governors respectively controlling said motors, a lever having lost motion connections with the transmission levers of both governors, a diaphragm exposed to the fluid pressure in said low pressure supply conduit, and connections between said diaphragm and said lever. 70

8. In combination, a mixed pressure turbine, a conduit admitting low pressure fluid thereto, a conduit admitting high pressure fluid thereto, low and high pressure valves controlling the passage of fluid through the 80 conduits, twin governors both responsive to speed changes of the turbine for controlling said valves, and a means responsive to pressure for modifying the action of one of the speed governors on the valve controlled 85 thereby.

9. In combination, a mixed pressure turbine, a conduit admitting low pressure fluid thereto, a conduit admitting high pressure fluid thereto, low and high pressure valves controlling the passage of fluid through the 90 conduits, a motor for actuating each of the valves, twin governors responsive to speed changes of the turbine for controlling the action of said motors, and a pressure responsive means for modifying the action of one 95 of the speed governors on the motor controlled thereby.

10. In combination, a mixed pressure turbine, a conduit admitting low pressure fluid thereto, a conduit admitting high pressure fluid thereto, low and high pressure valves controlling the passage of fluid through the 100 conduits, twin governors both responsive to speed changes of the turbine for controlling said valves, and a pressure responsive means that is common to and modifies the 105 action of both governors on said valves.

11. In combination, a mixed pressure turbine, conduits admitting low and high pressure fluid thereto, low and high pressure valves in said conduits, a pair of speed governors that are driven by and are responsive to changes in speed of the turbine for controlling said valves, the governors being so 110 adjusted that the one controlling the low pressure valve opens it fully before the other governor opens the high pressure valve, and closes them in the reverse order, and a means responsive to variations in pressure of the low pressure source for modifying 115 the action of a governor on the valve controlled thereby.

12. In combination, a mixed pressure turbine, conduits admitting low and high pressure fluid thereto, low and high pressure valve means for controlling the passage of fluid through the conduits, twin governors for the valves, and a pressure responsive 120 means which causes the low pressure valve 125

means to throttle its conduit when the supply of low pressure fluid decreases, said action being independent of the speed governor.

- 5 13. In combination, a mixed pressure turbine, conduits admitting low and high pressure fluid thereto, low and high pressure valve means for controlling the passage of fluid through the conduits, twin governors for the valves, and pressure responsive means which when the low pressure source of supply is deficient modifies the action of

the high pressure speed governor on its valve means and assumes control of the low pressure valve means to the exclusion of its speed governor and causes the same to restrict the opening to the turbine. 15

In witness whereof, I have hereunto set my hand this 8th day of November, 1911.

Correction in Letters Patent No. 1,089,709.

It is hereby certified that in Letters Patent No. 1,089,709, granted March 10, 1914, upon the application of Oscar Junggren, of Schenectady, New York, for an improvement in "Twin-Governor Mechanism for Mixed-Pressure Turbines," an error appears in the printed specification requiring correction as follows: Page 2, line 38, for the word "decrease" read *increase*; and that the said Letters Patent should be read with this correction therein that the same may conform to the record of the case in the Patent Office.

Signed and sealed this 31st day of March, A. D., 1914.

[SEAL.]

J. T. NEWTON,
Acting Commissioner of Patents.

means to throttle its conduit when the supply of low pressure fluid decreases, said action being independent of the speed governor.

- 5 13. In combination, a mixed pressure turbine, conduits admitting low and high pressure fluid thereto, low and high pressure valve means for controlling the passage of fluid through the conduits, twin governors for the valves, and pressure responsive means which when the low pressure source of supply is deficient modifies the action of

the high pressure speed governor on its valve means and assumes control of the low pressure valve means to the exclusion of its speed governor and causes the same to restrict the opening to the turbine. 15

In witness whereof, I have hereunto set my hand this 8th day of November, 1911.
